(57) **CLAIM**

An ornamental design for a combined butter spreader and knife, as shown and described.

DESCRIPTION

FIG. 1 is a perspective front view of the combined butter spreader and knife;

FIG. 2 is a first side view of the combined butter spreader and knife;

FIG. 3 is a second side view of the combined butter spreader and knife;

FIG. 4 is a top view of the combined butter spreader and knife;

FIG. 5 is a bottom view of the combined butter spreader and knife;

FIG. 6 is a first end view of the combined butter spreader and knife;

FIG. 7 is a second end view opposite, the first end view of FIG. 6, of the combined butter spreader and knife;

FIG. 8 is a cut away partial view of the combined butter spreader and knife taken across the lines 8-8 of FIG. 3;

FIG. 9 is a cross-sectional view of the combined butter spreader and knife taken across the line 9-9 of FIG. 8;

FIG. 10 is a cross-sectional view of the combined butter spreader and knife taken across the line 10-10 of FIG. 3;

FIG. 11 is a cross-sectional view of the combined butter spreader and knife taken across the line 11-11 of FIG. 3; and,

FIG. 12 is a cross-sectional view of the combined butter spreader and knife taken across the line 12-12 of FIG. 3.
